UNITED STATES PATENT OFFICE

ERNEST A. HALL, OF TOLEDO, OHIO, ASSIGNOR TO THE COLUMBIA BURNER COMPANY,
OF TOLEDO, OHIO, A CORPORATION OF OHIO

GAS FURNACE

Application filed April 22, 1929. Serial No. 356,978.

This invention relates to a furnace and more particularly to one which is adapted to be used in connection with a hot air heating system and in which gas is used as fuel.

5 The general object of the invention is to provide an improved arrangement, whereby the greater part of the combustion takes place in direct contact with the wall of the firepot, so that the heat generated is conducted directly to the air heating chamber, resulting in the highest possible efficiency and the utmost economy in the amount of fuel used. This involves not only an improved arrangement of a series of gas jets with respect to the wall of the firepot but also improved means for directing the flow of both the primary and secondary air supply.

The fuel is supplied through a burner ring or manifold and directed upwardly and outwardly against the wall of the firepot by a series of spuds having primary air inlet openings. The secondary supply of air is directed against the wall and combined with the primary mixture in a manner best suited to complete the combustion in contact with the wall. The direction and rate of flow of this secondary supply is controlled by means of a baffle resting preferably upon the burner ring and sloping upwardly toward the wall of the firepot, leaving a restricted annular space through which the products of combustion are discharged. In combination with the baffle, there may also be provided an adjustable top to adapt the same for the proper control of the air current in firepots of different sizes.

The preferred embodiment of the invention will be more particularly described in connection with the accompanying drawing, in which

Figure 1 is a vertical sectional view of the invention together with a portion of the furnace in which it is used.

Figure 2 is a similar view of a portion of the invention on an enlarged scale, the section being taken on the line 2—2 of Figure 3.

Figure 3 is a plan view of the burner, with parts broken away, showing also an adjustable top on the baffle for restricting the upward flow of gases from the burner.

Figure 4 is a vertical section through the upper part of the baffle, with the adjustable top mounted thereon.

Figure 5 is a section taken on the line 5—5 of Figure 3.

As shown in the drawing, the invention is mounted within a firepot having an outwardly bulged wall 5 and surrounded by an air heating chamber 6. The gas is supplied through a burner ring or manifold 7 which, in the present instance, is seated upon a circular plate 8 supported by a bar 9 or other suitable means. The ring 7 is preferably made in a number of separate sections, each connected to a gas supply pipe 10.

The ring 7 is provided with a series of upwardly and outwardly directed tubular members or spuds 11 mounted at equal distances along its periphery for discharging gas jets against the wall of the firepot. Each of these spuds is provided with suitable means, as for example, the openings 12, for initially mixing a small quantity of air with the gas to effect a primary combustion at or about the time of its impingement against the wall of the firepot, the ends of the spuds being at a predetermined distance from the wall such that the point of greatest heat coincides with the surface of the wall. A secondary supply of air to complete the combustion is directed, by means hereinafter described, against the wall of the firepot above the region of primary combustion. The ring 7 may be formed with a series of peripheral lugs 13 to gage the position of the burner and the spuds with relation to the firepot.

The secondary supply of air for completing the combustion is supplied through the annular space between the ring 7 and the wall of the firepot. For controlling the rate of flow and the direction of this secondary air supply, baffle sections 14 are mounted above the spuds 11, preferably resting upon the upper surface of the ring 7 in channels 15 formed between opposed flanges 16 extending upwardly from the burner ring. These baffle sections slope upwardly and outwardly from the burner ring and collectively present an inverted frusto-conical surface. The

flanges 16 serve to maintain them in this position independently of the wall 5.

As shown in Figures 1 and 2, the area of the space between the upper ends of the baffle sections 14 and the wall of the firepot is considerably less than the area of the space between the burner ring 7 and the wall of the firepot. This checks the upward flow of the air and, in connection with the outwardly 10 and upwardly sloping surface of the baffle, causes the secondary mixture to be effected and combustion to be completed in direct contact with the wall of the firepot. The restricted outlet and the consequent retarded 15 flow increases the contact of the hot gases with the wall and prevents the latter from being unnecessarily cooled by an excessive supply of cold air.

The same burner may be advantageously 20 used in a firepot of larger diameter by providing a top for the baffle, as indicated by the numeral 17 in Figures 3, 4 and 5. This top extends completely around the upper edge of the baffle and has a number of downwardly 25 projecting flanges 18 forming channels 19 between them either one of which is adapted to fit over the edge of the baffle, to reduce the area of the outlet. By providing a number of such channels 19 and by making the top 30 in a number of sections which overlap as at 20, the top may be adjusted to adapt it to firepots of different diameters. Each section of the top may be formed with an outwardly 35 projecting lug 21 which makes it impossible to adjust the top too close to the wall.

It is to be understood that the invention is not limited specifically to the form herein shown and described but includes all such modifications as fall within the scope of the 40 appended claims.

What I claim is:

1. In a gas furnace, the combination of a firepot, a burner mounted within the firepot and having upwardly and outwardly directed 45 gas outlets, spaced upstanding flanges on the burner forming a channel between them, and a baffle supported independently of the firepot wall by engagement between said flanges and presenting an outwardly 50 and upwardly sloping surface toward the wall of the firepot, thereby forming an upwardly converging space above the gas outlets to restrict the flow of the burned gas.

2. In a gas furnace, the combination of a firepot, a burner manifold disposed within the firepot and having spuds inclined upwardly and outwardly toward the wall of the firepot, a seat on which the manifold is supported, leaving a space between the manifold and the wall of the firepot for the air supply to the burner, a baffle extending upwardly 55 from the manifold and approaching the wall of the firepot above the spuds, and flanges 60 on the burner between which the base of the

baffle is held so that the baffle is supported independently of the firepot wall.

3. In a gas furnace, the combination of a firepot, a burner manifold disposed within the firepot and having upwardly and outwardly directed 70 gas mixing tubes, a seat on which the manifold is supported, leaving a space between the manifold and the wall of the firepot to supply air to the mixing tubes, and a baffle extending upwardly from the 75 manifold inside of said mixing tubes and approaching the wall of the firepot at a less inclination than the mixing tubes but supported independently of the wall and spaced therefrom sufficiently to provide a restricted 80 outlet for the burned gas.

4. In a gas furnace, the combination of a firepot, a seat disposed within the firepot, a burner manifold resting on said seat and having spuds inclined upwardly and outwardly 85 toward the wall of the firepot, the edge of said manifold being spaced from the wall of the firepot to provide for a supply of air to the spuds for the primary mixture, and to positively set the outlet ends of the spuds at 90 such a distance from the wall of the firepot that the point of highest flame temperature will coincide with the point of its impingement on the surface of said wall, the space between the wall and the manifold also providing for a current of air to complete the combustion as the flame flows along the wall.

5. In a gas furnace, the combination of a firepot, a burner manifold mounted within the firepot and having upwardly and outwardly directed gas outlets, a seat on which the manifold is supported, leaving a space between the manifold and the wall of the firepot to provide for a supply of air to the burner, a baffle resting on said manifold and made up of contiguous sections which collectively present an outwardly and upwardly sloping surface toward the wall of the firepot, thereby forming an upwardly converging space above the gas outlets to permit a restricted flow of the burned gas, and flanges on the burner between which the baffle sections are supported independently of the wall of the firepot.

6. In a gas furnace, the combination of a firepot, means for directing gas jets outwardly and upwardly toward the wall of the firepot, means including an inclined baffle located above the jets for directing a supply of air upwardly and outwardly against the 115 flame to complete the combustion, and radially adjustable means at the top of the baffle for restricting the discharge of the burned gas.

7. In a gas furnace, the combination of a firepot, a burner manifold within the firepot, a baffle extending upwardly from the burner manifold and cooperating with the wall of the firepot to define a combustion chamber, said burner manifold having out- 125 130

lets into said combustion chamber, said chamber having an air supply inlet and an outlet for the burned gas, said outlet being normally of smaller area than the inlet, and 5 radially adjustable means at the top of the baffle for partially closing said outlet to adapt it to firepots of large diameter.

8. In a gas furnace, the combination of a firepot, a burner within the firepot, a baffle supported by and extending upwardly from the burner, and radially adjustable means supported at the top of the baffle for partially cutting off the flow of burning gases from the burner.

15 9. In a gas furnace, the combination of a firepot, a burner within the firepot provided with spuds arranged to direct a primary mixture of air and gas against the lower part of the wall of the firepot, spaced flanges projecting upwardly from the burner inside of said spuds, and a baffle supported by the burner and by and between said flanges with its upper end approaching the wall of the firepot, whereby to direct a secondary supply 20 of air against said wall above the region where the primary mixture impinges thereon.

25 10. In a gas furnace, the combination of a firepot, a burner within the firepot provided with spuds arranged to direct a primary mixture of air and gas against the lower part of the wall of the firepot, a baffle supported on the burner with its upper end approaching the wall of the firepot, whereby 30 to direct a secondary supply of air against said wall above the region where the primary mixture impinges thereon, and a member supported by the upper end of the baffle and adjustable to restrict the upward flow of 35 gases from the burner.

40 11. In a gas furnace, the combination of a firepot, a burner within the firepot provided with spuds inclined upwardly toward the lower part of the firepot wall to direct a primary mixture of air and gas thereagainst, and a baffle supported on the burner with its upper end approaching the wall of the firepot at a less inclination than the spuds and above the same, whereby to direct a secondary supply of air against said wall above the region where the primary mixture impinges thereon.

45 12. In a gas furnace, the combination of a circular firepot, a burner manifold within the firepot provided with spuds inclined upwardly toward the lower half of the firepot wall to direct a primary mixture of air and gas thereagainst, and a baffle supported on said manifold inside the spuds with its upper portion approaching the wall of the firepot at a less inclination than the spuds and above the same, whereby to direct a secondary supply of air against said wall above the region where the primary mixture impinges 50 thereon, there being a clear annular open

space between the point on the wall where the primary mixture impinges and the lower part of the firepot, through which air is supplied for both the primary and secondary mixture.

55 13. In a gas furnace, the combination of a firepot, a burner manifold disposed within and in spaced relation to the firepot wall and having burner outlets directed toward said wall and arranged to discharge gas with a primary admixture of air, a baffle composed of sections extending upwardly from the manifold inside the gas outlets and approaching the wall of the firepot above the region of combustion to deflect toward said wall the current of air passing between the gas outlets, thereby providing a secondary supply of air to complete the combustion, and means associated with the manifold and the base of the baffle inside the burner outlets to support 60 the baffle independently of the firepot wall.

65 14. In a gas furnace, the combination of a firepot, a burner structure within the firepot and provided with means for discharging gas with a primary admixture of air toward the wall of the firepot, there being sufficient space to supply an upward current of air between the burner structure and the firepot wall, inside of the flame, and a baffle supported above the burner structure and independently of the firepot wall at such an inclination as to deflect said current of air against the gas flame above the region where the latter impinges against the firepot wall, whereby said deflected current constitutes a 70 secondary supply of air to complete the combustion.

75 In testimony whereof I have hereunto signed my name to this specification.
